We claim the ornamental design for a lifter for washing machine, as shown and described.

DESCRIPTION

FIG. 1 is a front/right-side/top perspective view of a lifter for washing machine showing our new design;
 FIG. 2 is a front elevational view thereof;
 FIG. 3 is a rear elevational view thereof;
 FIG. 4 is a left-side elevational view thereof;
 FIG. 5 is a right-side elevational view thereof;
 FIG. 6 is a top plan view thereof;
 FIG. 7 is a bottom plan view thereof; and,
 FIG. 8 is a perspective view thereof shown in its environment. The broken line showing of bottom details in FIG. 7 is included for the purpose of showing portions of the lifter for washing machine that form no part of the claimed design. The broken line showing of a washing machine in FIG. 8 depicts environmental structure that also forms no part of the claimed design.
